CARTON

George Rottman, Brooklyn, N. Y.

Application December 1, 1942, Serial No. 467,488

3 Claims. (Cl. 211—32)

My invention relates to new and improved cartons which can be used for holding hats and other articles of clothing, in order to protect the same from dust, moths and the like.

The principal object of my invention is to provide cartons which can be simply manufactured and assembled from a plurality of blanks. One of these blanks may comprise the body of the carton and the other blank may comprise the cover of a carton.

Another object of my invention is to provide improved forms for hats, to be used in said cartons.

Other objects of my invention will be set forth in the annexed description and drawings, which illustrate preferred embodiments thereof.

Fig. 1 is a section on the line 1—1 of Fig. 2, which shows one embodiment of the invention.

Fig. 2 is a section on the line 2—2 of Fig. 1.

Fig. 3 is a section on the line 3—3 of Fig. 1.

Fig. 4 is a perspective view of the bracket which is used in the embodiment of Figs. 1—3.

Fig. 5 is a plan view of the blank which is set up to make the bracket of Fig. 4.

Fig. 6 is a side elevation of said bracket of Fig. 4.

Fig. 7 is an elevation, partially in section, of another embodiment.

Fig. 8 is a section on the line 8—8 of Fig. 7.

Fig. 9 is a plan view of the blank which is set-up to make the bracket of the embodiment of Fig. 7.

Fig. 10 shows another embodiment, which has a different form of bracket.

Fig. 11 is a plan view of the blank which is set up to make the bracket of Fig. 10.

Fig. 12 shows still another embodiment, which is provided with protective means against soiling the brim of the hat and with locking means to hold the hat in position when shipping.

Fig. 13 is a section on line 13—13 of Fig. 12.

Fig. 14 is a detailed plan view of the bracket of Figs. 12 and 13, with the protective means attached thereto in unfolded position and with the locking means in inoperative position.

Fig. 15 is a perspective of the bracket which is used in the embodiment of Figs. 12—14.

Referring to Fig. 1, this shows an element 54, which may have a closed bottom and an open top, or which may be open at its top and bottom.

Said element 54 has one or more pairs of brackets B. Each bracket B is made of bendable cardboard or the like. Each bracket B has a top leg 55, a ledge 56 which is provided with a sleeve 57 which is made of felt or other soft

material, an inclined leg 58, and an upwardly bent leg 59 which has a slot 60. Said slot 60 has respective lateral offsets 61 at its ends. The blank which is shown in Fig. 5 is bendable along the lateral lines L. The top leg 55 is fixed to the wall of element 54 by the headed fastener 62.

The shank of a headed fastener 63 is located in slot 60. When the shank of fastener 63 is located in lower offset 61, which acts like a bayonet joint, the ledge 56 is held in the operative horizontal position of Fig. 1. The leg 59 can be moved laterally so as to release the bottom offset 61 from the shank of fastener 63. Leg 59 can then be slid downwardly until the shank of fastener 63 is aligned with the top offset 61. Ledge 56 may then be substantially vertical. The shank of fastener 63 can then be interlocked with top offset 61. When leg 59 is slid to its bottom position, ledge 56 may be still substantially inclined away from the wall of element 54.

Two hats can thus be held in partially nested formation upon the respective pairs of ledges 56. Hence the vertical wall of element 54 can be made and shipped in original flat sheet form, with the brackets lying flat against said flat sheet form, and with the flat bracket elements parallel to each other. The flat legs 59 and 58 will then abut each other.

The bracket of Figs. 7—9 has a leg 59a which extends downwardly from the inclined leg 58, when said bracket is set up. Said leg 59a has a keyhole slot 60a, whose end 60b is sufficiently large to enable the head of fastener 63 to be passed through said slot-end 60b. Hence the element 54 can be made and shipped as a flat blank, with the flat blanks of the brackets connected thereto by the respective fasteners 62. Each bracket is set up by passing the head of the respective fastener 63 through the slot-end 60b and then moving the bracket relative to said fastener 63, until the shank of said fastener 63 is located in the slot 60a, whose width is less than the width of the head of fastener 63.

In each of said embodiments, each bracket may be turnable around the shank of the respective fastener 62.

The embodiment of Figs. 10 and 11 shows a double bracket of the type shown in Figs. 4—6, so that the brim of each hat is clamped in position between the respective horizontal ledges 56. Each leg 55, which is fixed or turnably connected to element 54 by the headed fastener 62, is located between a pair of ledges 56.

Referring to the embodiment illustrated in

Figs. 12-15, bracket B₁ is similar in construction to bracket B of the embodiment illustrated in Figs. 1-6, heretofore described. The said bracket B₁ is secured to the wall 54 in the same manner as said bracket B. Bracket B₁ is set in the operative position the same as bracket B, heretofore described.

Bracket B₁ is provided with a cloth member 70 which is secured to ledge 56 of said bracket by means of a staple 71. There is positioned on the top face of cloth member 70 adjacent its secured end, a reinforcing strip 72. Staple 71 passes through the cloth member 70 and reinforcing member 72.

The opposite end 70a of cloth member 70 is free and is folded in the manner illustrated in Fig. 12. The brim 13 of hat H is held within the folded portion of the free end 70a. In this manner, the hat is protected against soiling.

To prevent cloth member 70 from unfolding, a locking member 74 is secured to ledge 56 of bracket B₁ by means of the rivet 75. The said member 74 is turnable as shown in Figs. 14 and 15. Not only does locking member 74 hold cloth member 70 in the proper position, but it also locks brim 13 of hat H so that the hat will not become dislodged while shipping.

I have disclosed several of the embodiments of my invention, but it is clear that numerous changes and omissions can be made without departing from its scope.

5 I claim:

1. A hat-supporting device comprising a wall, a pair of brackets located at the inner face of said wall, each said bracket having a first leg which is connected to said wall, each said bracket having a second leg which is slidably connected to said wall, each said bracket being made from a transversely bendable blank, each said bracket having an intermediate leg which is held parallel to said wall when its second leg is in a first predetermined position, said intermediate leg being outwardly inclined from said other legs when said second leg is slid to a second predetermined position.

2. A hat-supporting device according to claim 1, in which each of said brackets is provided with locking means for holding the brim of the hat.

3. A hat-supporting device according to claim 1, in which each of said brackets is provided with protective means for preventing the soiling of the hat.

GEORGE ROTTMAN.
